METHOD AND APPARATUS FOR MANUFACTURING THORIATED FILAMENT DEVICES

Raymond R. Hoffman, St. Mary's, Pa., assignor to Hygrade Sylvania Corporation, Salem, Mass., a corporation of Massachusetts

Application January 4, 1936, Serial No. 57,474

6 Claims. (Cl. 250—27.5)

This invention relates to incandescent filament devices and more particularly to processes of carbonizing electrodes for such devices.

In certain devices for example those employing electron emitters of the thoriated tungsten type, it has been the practice to subject the electrode containing thorium, to a carbonizing process so that an appreciable quantity of the thorium may be reduced subsequently to thorium. Inasmuch as so-called thoriated tungsten cathodes depend for their emitting properties on what is believed to be a layer of thorium of atomic thickness proportions, it is very difficult with ordinary methods of processing to produce cathodes in large quantities with a high degree of uniformity as regards emission characteristics. Because of this condition it has not been found practicable heretofore to effect the carbonization of thoriated tungsten cathodes on the usual automatic exhaust and sealing machine.

I have found that by accurately and automatically controlling the pressure of the carbonizing gas, as well as the cathode temperature during the carbonizing and by accurately controlling the duration of the carbonizing process, it is possible to carbonize thoriated tungsten filaments or cathodes on the usual automatic exhaust and sealing machines. As a result it is possible to produce great quantities of thoriated tungsten devices such as radio tubes, with a very high degree of uniformity as between the various tubes.

An object of the present invention is to provide an improved method of processing a thoriated tungsten cathode device.

Another object is to provide an automatic mechanism for controlling with a high degree of accuracy the various factors encountered in the carbonization of thoriated tungsten electrodes and the like.

A feature of the invention relates to a mechanism which automatically and accurately controls the pressure of the carbonizing gas in the tube or other device to be carbonized.

Another feature relates to an improved form of lamp or tube exhaust and sealing machine having means to effect the carbonization of one or more electrodes during the operation of the machine.

A further feature relates to an improved automatic valve controlling arrangement for lamp or tube exhaust machines for filling the lamp or tube with gas at a predetermined pressure.

A further feature relates to the novel organization, arrangement and relative location of parts which go to make up an improved machine for

exhausting, carbonizing and sealing devices having one or more thoriated tungsten electrodes.

Other features and advantages not specifically enumerated will be apparent after a consideration of the following detailed descriptions and the appended claims.

While the invention will be described herein as embodied in one well-known type of exhaust and sealing machine it will be understood that it is equally well applicable to other forms of automatic exhaust and sealing machines. Furthermore inasmuch as automatic exhaust and sealing machines for lamps, radio tubes and the like are quite well-known in the art the drawing is intended to be merely diagrammatic as to details of structure of the machine as a whole. Accordingly, in the drawing,

Fig. 1 is a schematic diagram of certain parts of any well-known form of automatic exhaust and sealing machine.

Fig. 2 is a detailed schematic diagram of certain parts of the machine of Fig. 1.

Referring to Fig. 1, there is schematically illustrated an automatic exhaust and sealing machine such for example as illustrated in detail in Patent 996,936. In general, the machine includes a rotatable spider carrying a series of arcuate hollow sectors 1, 2 and 3 each sector being provided with a plurality of ports 4 to receive the lamps or tubes to be processed. The spider is rotated in a step-by-step manner in the direction of the arrow by any suitable mechanism, for example by the Geneva gear 5, which is operated from the main driving motor 6 it being understood that the Geneva movement has the same number of teeth as the number of ports 4. Each of the ports 4 is connected by suitable piping to the central rotary valve designated generally by the numeral 7 the rotary valve being provided in the well-known manner with a series of ports equal in number to the ports 4 so that as each lamp or tube is advanced to successive positions the particular processing for that position is effected. In the particular machine illustrated the lamps are indexed to twenty-four successive positions which are indicated in the drawing by the numerals 1 to 24 inclusive. In positions 1, 2 and 3 the ports 4 are closed so that the tubes may be loaded into the machine. In positions 4 to 10 inclusive the ports are connected through the rotary valve 7 with the first exhaust pump. In position 5 the tube is tested for leaks by any well-known mechanism. From positions 6 to 15 there is provided a suitable oven for baking out the glass and other parts of the tube. In positions 16 to 24 the ports are connected through the rotary valve 7 with the second exhaust pump.

12 to 23 inclusive the tubes are connected to the final exhaust pump and while passing from positions 12 to 23 various operations are performed. Thus in positions 12 and 13 the filament is degassed by being raised to a high temperature. In position 14 the filament is unlighted thus allowing the tube to cool somewhat before it reaches position 15. In position 15 the automatic control mechanism illustrating schematically in Fig. 2 10 operates to admit the carbonizing gas at a predetermined pressure. In positions 17 to 23 the filament is again lighted and the bombarding coil is lowered over the tube to raise the temperature of the metal parts to drive out occluded gases 15 and in position 23 the bombarding coil acts to flash the getter material within the tube. Position 24 is the tipping-off position where the exhaust tubulation is sealed off. For convenience of understanding, the sequence of operations is 20 according to the following schedule:

Port No.	
1	Closed—tube loading
2	Closed
3	Closed
25	4 Manifold
5	Leak detector
6	Manifold
7	Manifold
8	Manifold
9	Manifold
10	Manifold
11	Manifold
30	12 Single pump
13	Single pump
14	Single pump
15	Single pump
16	Single pump
17	Single pump Bombarding coil
18	Single pump
19	Single pump Bombarding coil
20	Single pump
21	Single pump Bombarding coil
22	Single pump
23	Single pump Getter flash coil
24	Closed—tipping-off

Lighting positions

Referring to Fig. 2 a detailed description will 40 now be given of the apparatus which comes into operation when the tube reaches position 15. As shown in Fig. 2 port No. 15 of the rotary valve is connected by pipe 16 of glass or other suitable material to the exhaust pump and also by pipe 18 to a supply of carbonizing material. Preferably the source 19 supplies substantially pure acetylene gas and the gas system is preferably so designed that the gas does not come in contact with any materials which will cause contamination. Interposed in the line 18 is any well-known form of pressure regulator 20 and also a constriction 21 whereby the gas is allowed to flow at a 45 relatively slow but uniform rate. The flow of the carbonizing gas into the tube being processed is controlled by any well-known form of valve indicated schematically in the drawing by the numeral 22. This valve may be of the clamp type or of the needle valve type and is arranged to be electromagnetically operated by an electromagnet 26 which is normally deenergized except when the tube reaches position 15 as will be described. The 50 exhaust line 24 is also provided with a suitable valve 25 which may be similar to valve 22 and provided with an operating electromagnet 26 which is so arranged that the valve 25 is normally open except when the carbonizing gas is being admitted to the tube. For the purpose of controlling the timed operation of valves 22 and 25 there are provided a cam-controlled mercury switch 27 and an electromagnetic relay 28, the latter being normally deenergized as indicated in the drawing. Preferably although not necessarily the machine is supplied with operating current from any suitable source for example from 55 the alternating current bus bars 29, 30 and in

order to effect the operation of the master relay 28 preferably the current from the supply conductors 29, 30 is rectified by a rectifier device 31 which may take the form of a vacuum tube rectifier, or a mercury vapor type rectifier. The heater or filament 32 of this rectifier is supplied with alternating current from the lines 29, 30 through step-down transformer the secondary of which has its electrical mid-point connected by conductor 33 to one terminal of the winding of relay 10 28, the anode or anodes 34 being connected to the line 30. The energizing circuit for master relay 28 is completed under control of the manometer 35 which is interposed in the line 16 as shown. This manometer may be of any well-known construction and in the particular embodiment shown it includes a mercury column 36 the level of which is dependent upon the pressure in the line 16. Preferably the manometer is provided with a sealed-in contact 37 which when the pressure 20 in line 16 reaches a predetermined value, completes the energizing circuit for master relay 28, this circuit being traceable from line 30, conductor 38, rectifier 31, conductor 33, winding of relay 28, conductor 39, contacts 37, 36, conductor 40 25 to line 29.

From the foregoing it will be seen that the master relay is normally deenergized to maintain the contacts 41, 42 closed, thus preparing a circuit for valve magnet 23 this circuit however 30 being also controlled by the mercury switch 27. Switch 27 is controlled by a cam 43 which is driven at the required rate so that the cam makes one revolution for each indexing step of the machine. Likewise switch 44 is operated by 35 a cam 45 which makes one revolution for each indexing step, the switches 27 and 44 remaining closed while each tube is in position 15. When therefore, the tube reaches position 15, a circuit is completed from line 30, conductor 46, winding of magnet 23, contacts 41, 42 to line 29. Magnet 23 being thus energized opens the valve 22 permitting the acetylene from source 19 to flow into the tube. A parallel circuit can be traced through the normally closed manually operable switch 47 and the winding of magnet 26 causing the valve 25 to be closed. When the predetermined pressure of acetylene has been admitted into the tube, the mercury column 36 makes contact with electrode 37 causing the 45 operation of the master relay 28 which thereupon opens contacts 41, 42. The operation of relay 28 causes the deenergization of magnets 23 and 26. If desired the relay 28 may be of the fast-to-release but slow-to-operate type so that the 50 acetylene may be maintained in the tube for a predetermined interval while the tube is in position 15. It will also be noted that when the acetylene has been admitted to the tube the switch 44 completes a circuit over the conductors 48, 49 to cause the filament of the tube to be 55 lighted. The duration of lighting of the filament is accurately timed since it is directly controlled by the indexing motion of the machine. By the foregoing arrangement it is possible therefore to admit pure acetylene at a fixed predetermined pressure and to maintain the filament at a predetermined carbonizing temperature and for a 60 fixed predetermined interval of time.

When the tube which has thus been carbonized is indexed to position 16 switches 27 and 44 are subjected to the same cycle of operation and release to cause the next tube to be flashed and carbonized as above-described. The carbonized tube is advanced to the succeeding positions as 70 75

schematically enumerated in the above schedule and in position 24 the exhaust tubulation is sealed-off and the tube removed from the machine. It will be understood of course, that the foregoing cycle of operations is repeated for each tube that is loaded into the machine.

Various changes and modifications may be made herein without departing from the spirit and scope of the invention.

10 5 What I claim is:

1. In an automatic exhaust machine of the character described, the combination of means to advance a bulb having an electrode to a plurality of successive positions where different operations are to be performed on said bulb, means automatically effective at one of said positions to admit a carbonizing gas into said bulb, means effective to shut off the gas supply when a predetermined pressure is reached in said bulb, and 10 means to heat said electrode to a predetermined temperature in the presence of said gas.

2. In an automatic machine of the character described the combination of means to advance a bulb having an electrode to a plurality of successive positions where different operations are to be performed on said bulb one of said positions being a carbonizing position, a source of carbonizing gas, a normally closed valve in the line connecting said source to said carbonizing position, a vacuum pump, a normally open valve in the exhaust line from said pump, means automatically effective when said bulb reaches the carbonizing position to open the first-mentioned valve and to close the second-mentioned valve, and means effective to close the first-mentioned valve when a predetermined pressure of the carbonizing gas is in the bulb.

3. In an automatic exhaust machine of the character described, the combination of a platform to carry a bulb having an electrode, means to index said platform in a step-by-step motion to a plurality of successive positions, means effective in at least one of said positions to subject the bulb to a preliminary exhaust, means effective in at least one other position to subject the bulb to a final exhaust, and means effective in an intermediate position to admit a carbonizing gas into the bulb and automatically effective in said intermediate position to shut off the supply of carbonizing gas when a predetermined pressure is in the bulb.

4. In an automatic machine of the character described the combination of a platform to receive a bulb to be exhausted, means to index said platform to a plurality of successive positions one of said positions being a carbonizing position, a 5 source of carbonizing gas, a valve in the supply line from said source, an exhaust pump, a valve in the exhaust line from said pump, a master relay, a pair of switches operated when said bulb reaches said carbonizing position one of said 10 switches arranged to close an electrical heating circuit for an electrode in said bulb, the other of said switches arranged to complete a circuit including contacts of said master relay, a pressure-controlled relay controlling the first-mentioned 15 valve and responsive to a predetermined pressure of carbonizing gas in the bulb to operate said master relay.

5. In combination a bulb having an electrode to be carbonized, a source of carbonizing gas, a 20 line connecting said source to said bulb, an exhaust line through which said bulb can be exhausted, a valve in each of said lines, an electromagnet for controlling each valve, a master relay having at least one normally closed contact, 25 an automatic switch effective when operated to close a circuit through the gas-control valve to open the same and to close a circuit through the exhaust control valve to close the same, both of said circuits being controlled by the said contact 30 of said master relay, a pressure-controlled relay, and a circuit for said master relay controlled by said pressure-controlled relay.

6. In combination a bulb having an electrode to be carbonized, a gas-control valve, an exhaust-control valve, means for normally maintaining the gas-control valve closed and exhaust-control normally valve open, a master relay controlling both of said valves, a pair of automatic switches one of said switches when operated causing the 40 opening of the gas-control valve and the closing of the exhaust-control valve the other of said switches completing a heating circuit for said electrode, and a pressure-controlled relay responsive to the attainment of a predetermined 45 pressure of carbonizing gas in the bulb to cause the closing of said gas-control valve and the opening of said exhaust-control valve.

RAYMOND R. HOFFMAN. 50
